UNITED STATES PATENT OFFICE.

HENRY L. PITMAN, OF WESTFIELD, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

Application filed June 12, 1923. Serial No. 644,841.

To all whom it may concern:

Be it known that I, HENRY L. PITMAN, a citizen of the United States, residing in Westfield, in the county of Union and State 5 of New Jersey, have invented certain new and useful Improvements in Combined Typewriting and Computing Machines, of which the following is a specification.

This invention relates to numeral-key-10 locking means and ribbon-shifting means.

In combined typewriting and computing or "bookkeeping" machines of the Underwood-Hanson type, the machine is normally set for addition, and the ribbon-shifting 15 means is connected with the subtraction-setting means; so that, upon setting the machine for subtraction, the color of printing is changed, numbers to be added usually being typed in black, and numbers to be sub-20 tracted usually being typed in red. In some machines of this type, provision is made of means to lock the numeral-keys when the carriage reaches a zone in which subtraction is to be effected, the locking 25 means being rendered ineffective by depression of the subtraction-key or of the non- compute key. In other machines of the type referred to, provision is made of means for disconnecting the ribbon-shifting mecha-30 nism from the subtraction-setting mecha- nism when certain subtraction-zones are reached, to cause subtraction to be effected in black, and of means for resetting the machine to add and type in red in such zones.

In practice it has been found desirable to 35 lock the keys when the carriage reaches certain computing zones, irrespective of the form of computation to be effected in such zones, and to provide means, controlled by 40 suitable keys, to release the numeral-keys and determine the setting of the machine for addition or subtraction in that zone. It has also been found desirable to have the amounts typed in certain columns on the 45 work-sheet to appear in red when subtracted and in black when added, and in other columns to appear in black when subtracted and in red when added.

It is an object of the present invention to 50 provide simple and effective means for effecting such desired results.

According to one form of the invention, provision may be made of addition-setting means and subtraction-setting means oper-55 able by addition and subtraction keys, re-

spectively, and of suitable color-changing means normally under the control of both the addition-key and the subtraction-key.

Provision may also be made of numeral-key-locking means rendered effective by the 60 carriage when the latter reaches certain computing zones and releasable by depression of the addition-key, the subtraction-key or a non-compute key.

The color-changing means may be placed 65 under the exclusive control of either the addition-setting means or the subtraction-setting means, the first result being effected by operation of the numeral-key-locking means, and the second result being effected directly 70 by the carriage.

To obtain the desired results for different computing zones, certain of the column- 75 stops on the carriage may be provided with suitable means for operating the numeral- key-locking means only, and thereby plac- ing the color-changing mechanism under the control of the subtraction-setting mecha- nism, or for locking the numeral-keys and placing the color-changing means under the 80 exclusive control of the addition-setting means. Use may also be made of column- stops which have no effect on the numeral- key-locking means or on the color-changing 85 mechanism.

Other features and advantages will hereinafter appear.

In the accompanying drawings,

Figure 1 is a side elevation, partly in section, showing the invention as applied 90 to an Underwood-Hanson bookkeeping ma- chine.

Figure 2 is a detail view of the escape- 95 ment mechanism.

Figure 3 is a skeleton perspective view 95 of part of the structure shown in Figure 1.

Figure 4 is a fragmentary view, illustrating the locking of the keys as the carriage reaches a computing zone, and showing the 100 color-signal disconnected from the subtraction-setting mechanism.

Figure 5 is a view similar to Figure 4, but showing the keys unlocked by the actua- 105 tion of the subtraction-key, and the state- signal shifted to show, in connection with the color-signal, black subtraction.

Figure 6 is a view similar to Figure 4, but showing the keys released by depression of the addition-key, and the color-signal 110 shifted to indicate red addition.

Figure 7 is a view similar to Figure 4, but showing the color-signal under the exclusive control of the subtraction-setting mechanism.

5 Figure 8 is a view similar to Figure 7, but showing the numeral-keys unlocked by the subtraction-key, and both the color and state signals shifted to indicate red subtraction.

10 Figure 9 is a view similar to Figure 7, but showing the numeral-keys unlocked by the addition-key and the color and state signals in their normal positions, to indicate black addition.

15 Figure 10 is a view showing the numeral-keys unlocked by the non-compute key.

20 Figure 11 is a fragmentary rear view showing the relation of one of the controlling stops to the devices for controlling the mechanism and the color-signal, for actuating the key-lock and for automatically tripping the general operator.

25 Figure 12 is a rear elevation, partly in section, of a portion of the structure shown in Figure 10.

30 Upon depression of an alphabet-key 15 or a numeral-key 16, a corresponding type-bar 17 acts through a bell-crank 18 to swing a type-bar 19 upwardly and rearwardly to cause types 20 thereon to type on a work-sheet on the platen 21, rotatably supported in a carriage 22 movable transversely of the machine on front and rear rails 23 and 24, respectively. The carriage 22 is normally urged to the left by a spring-drum, not shown, and its movement in such direction is controlled by means of suitable escapement mechanism comprising an escapement wheel 25, connected with the carriage by means of a rack 26 pivotally mounted on the carriage and normally in engagement with a pinion 27, having a usual one-way connection with the escapement wheel 25.

35 The escapement wheel 25 is normally held against rotation under the influence of the spring-drum by means of a loose dog 28 mounted on a dog-rocker 29 provided with a fixed dog 30. When an actuated type-bar 19 approaches its printing position, a shoulder 31 thereon engages a bar 32 forming part of a universal frame 33 and moves the same rearwardly to rock the dog-rocker 29 sufficiently to carry the loose dog 28 out of engagement with the escapement wheel and the fixed dog into engagement with the escapement wheel. During the return movement of the type-bar, the universal frame 33 and the dog-rocker 29 return to their normal positions, the loose dog again coming into engagement with the escapement wheel 25 and permitting a letter-feed movement of the carriage 22 in the usual manner.

40 In order that type-impressions may be made on a work-sheet on the platen when the types are swung against the latter, pro-

5 vision is made of a ribbon 34 threaded through the upper end of a ribbon-vibrator 35. The ribbon-vibrator 35 is normally in such a position that the ribbon 34 lies beneath the printing line, but, upon rearward 70 actuation of the universal frame 33, the ribbon-vibrator 35 is moved upwardly, to bring the ribbon 34 to effective position, by means of a lever 36 connected with the ribbon-vibrator 35 at its lower end. Said lever 36 is 75 mounted to swing about a fixed pivot 37, and has an upwardly-projecting rear end provided on opposite sides with pins 38 and 39 at different distances from the pivot 37, the connection between the lever 36 and the 80 universal frame 33 being effected by means of a frame 40 slidable on the universal frame 33 to bring one or the other of its slotted sides into engagement with the right-hand pin 38 or the left-hand pin 39 to cause the 85 ribbon to be lifted for typing through the upper black zone or through the lower red zone.

85 At its rear the carriage is provided with rods 41 and 42 along which denomination-selectors 43 may be set, as desired, each denomination-selector being swingable about and slidable along the rod 41, and being held in adjusted position along the rod 41 by means of a tooth 44 to engage with one of a 90 series of notches in the rod 42. Each denomination-selector 43 is set to determine in connection with a zone-controller 45 a computing zone on a work-sheet on the platen. Such zone-controller is in the form of a roller with tapered ends, and, as the carriage enters the computing zone, a frusto-conical roller 46 on the denomination-selector 43 rides up on the zone-controller 45 to 95 raise a selector-dog 47 on the denomination-selector into position to actuate seriatim a plurality of denominational jacks 48. Each jack 48 is swung about a pivot 49 and acts through a downwardly-extending thrust-rod 50 to rock the corresponding lever 51 100 of a series associated with a series of transposition linkages 52, one for each lever 51, and a series of bell-crank 53 actuatable by said linkages 52 to advance computation-members or rack-bars 54 into position with index-pins 55 thereon immediately beneath the corresponding pin-setting bars 56, so that, upon depression of one of the pin-setting bars 56 by the corresponding numeral-key 16, the corresponding pin on the selectively advanced bar will be depressed or set.

105 To actuate the pin-setting bars 56, each of the numeral-key-levers is provided with a pendant 57, which, as the numeral-key approaches the lower end of its stroke, strikes an arm 58 on a rock-shaft 59, of which there is one for each pendant 57, except that on the "0" key-lever, and rocks the same to actuate a linkage 60, of which one of the pin-setting bars forms a part, thereby de- 110

pressing such pin-setting bar 56 to set the pin of the corresponding value on one of the denominational members 54.

After a number has been so indexed digit by digit on the pins 55 of the different computation-members 54, a handle 61 may be drawn forwardly to rock a shaft 62 carrying toothed sectors 63 meshing with pinions 64, which, in turn, mesh with racks 65 forming part of a general operator 66, thereby advancing the general operator to cause a cross-bar 67 thereon to engage the depressed pins 55 and advance the rack-bars or computation-members 54 distances proportional to the values of the index-pins 55 in depressed position. At their forward ends the rack-bars 54 are provided with racks 68 meshing with pinions (not shown), having one-way connections with dials or dial-wheels 69, so that, upon advance of the general operator, the number indexed on the pins 55 will be run into the dial-wheels 69, and the result may be read through a sight-opening 70 in a computer-casing 71. In practice the handle 61 is usually removed from the machine and the general operator is reciprocated by a power device thrown into operation manually by a key or automatically by the carriage by means to be described hereinafter.

In machines of the Underwood-Hanson type, subtraction is usually effected by the well-known complementary method. To set the machine for subtraction, provision is made of a subtraction-key 72, which, when depressed, acts through a link 73 to swing rearwardly against the action of a spring 74 an upstanding arm 75 fixed on a shaft 76, thereby rocking the latter to withdraw a hook 77 thereon from engagement with a notch 78 in a subtraction-bar 79, and permitting the subtraction-bar to be drawn rearwardly by a suitable spring 80. In its rearward movement the subtraction-bar 79 acts to set the "9" pins on all of the computation-members 54 by means (not shown), and also to shift the connections between the shafts 59 and the corresponding linkages 60, so that, upon depression of a numeral-key, the pin-setting bar 56 usually actuated thereby remains at rest and the bar 56 complementary thereto is actuated, thereby setting the pin on the selected computation-member 54 and restoring the corresponding "9" pin on that computation-member to normal or unset position. In the rearward movement of the subtraction-bar, a pin 81 thereon projecting through the slotted end of an arm 82 swings the same rearwardly, and consequently rocks in a counterclockwise direction a shaft 83, on which the arm 82 is fixed. Fixed on the shaft 83 is a forwardly-extending arm 84 having a forked end receiving a pin 85 on an arm 86 projecting rearwardly from a bar 87 pivoted at

its upper edge and extending at its lower edge into notches 88 in said shafts 59, so that the rocking of the shaft 83 by the rearward movement of the subtraction-bar 79 causes the shafts 59 to be advanced to change their connections with the linkages 60. For a fuller disclosure of the subtraction-setting mechanism, attention is called to the patent to Adolf G. Kupetz, No. 1,452,162, dated April 17, 1923.

In order to indicate the color in which typing is to be effected and the state, addition or subtraction, for which the machine is set at any time, provision is made of a color-signal 89 having two color fields 90 and 91, usually red and black, respectively, and a state-signal 92 having "A" and "S" thereon to indicate addition or subtraction settings, the letters on the state-signal being displayed through openings 93 in the color fields, and the state indications and color indications being displayed through a sight-opening 94, in a shield 95 secured on the front of the machine, of sufficient size to show a ring of the colored field around the opening therein through which the state-signal is displayed.

The color-signal 89 is mounted on an upright arm 96 of a lever 97 fixed on the forward end of a shaft 98 and having an arm 99 projecting to the right and urged downwardly by a spring 100 connected thereto and to a pin 101 projecting rearwardly from the front plate 102 of the typewriter-frame. An arm 103 is fixed to the shaft 98 near its rear end, and to the outer end of said arm 103 is pivoted a depending link 104 passing through a slot 105 in a plate 106 projecting forwardly from a fixed bar 107 of the typewriter-frame. Said link 104 is normally positioned above a vertical plunger 108 pivoted to the rear end of an arm 109 fixed on the shaft 83, so that, upon rearward movement of the subtraction-setting bar 79, the plunger 108 will be lifted and the color-signal will be shifted from its normal position, indicated in Figure 4, to the position indicated in Figure 6, to display the red field 90 through the sight-opening 94. The slot 105 is, however, of suitable extent to permit the depending link 104 to be moved forwardly out of the path of the plunger 108 by means to be described hereinafter. A connection between the color-signal 89 and the shiftable frame 40 of the ribbon-vibrating mechanism is effected by means of an arm 98^a fixed on the shaft 98 and a link 98^b connecting said arm 98^a and the frame 40.

The state-signal 92 is mounted on an upright arm 110 of a lever 111 pivoted on the shaft 98, and having a leftwardly-extending arm 112 to which is attached one end of a spring 113 attached at its other end to said pin 101. The lever 111 is connected by a rearwardly-extending bail 114 with an arm

115 projecting to the left, and having pivoted thereto a pendent link 116 passing through a slot 117 of said plate 106 and held in alignment with said plunger 108, so as 5 always to be under control thereby. It will be seen that, upon subtraction-setting, both the state and color signals will ordinarily be shifted from their Figure 7 to their Figure 8 positions, but, in case the link 104 is moved 10 out of the path of the plunger 108, the upward movement of the plunger will not effect a shifting of the color-signal, and the signals will be set as indicated in Figure 5.

To tabulate the carriage to a computing 15 zone, use may be made of the usual tabulating mechanism comprising tabulator-keys 118^a and column-stops 118 properly positioned along a notched bar 119 at the rear of the carriage. After the digit of lowest designation has been typed in a computing 20 column or zone, the letter-feed movement of the carriage causes the corresponding stop 118 to engage a dog 120 on a trip-lever 121 to rock the same about its pivot 122 and to 25 lift a link 123 attached at its lower end to an arm 124 fixed to a bail 125 mounted on a pivot 126. Such lifting of the arm 124 acts, through the bail 125, to swing an arm 127 connected with the other end of the bail to 30 withdraw a link or latch 128 from the path of an arm 129 mounted on a pivot 130 and urged upwardly by a spring 131. Upon such release, the arm 129 is swung upwardly and a forwardly-projecting arm 132, forming 35 with the arm 129 a lever 133, is swung downwardly, and, through a pin 134 projecting from a vertical slide 135, depresses the latter, thereby rocking a lever 136 and lifting a controlling pin 137 to throw into operation 40 a motor mechanism, indicated in general by 137^a, to cause a complete cycle of the general operator. During the forward movement of the general operator 66, a cam 66^a thereon engages an offset forward end 132^a of the lever 133 and restores it to normal position 45 to be locked by the latch 128.

Certain of the stops 118 are provided with 50 extensions 138 to shift the controlling link 104 out of the path of the plunger 108, so that setting of the machine for subtraction will not shift the color-signal. Such extensions 138 are of sufficient length to engage, before the carriage enters the computing zone, a dog 139 mounted on a lever 140 and swing the latter about its pivot 122 to lift a link 141 connected at its lower end with an arm 142 fixed on a shaft 143, thereby rocking the shaft against the action of a spring 144. Also fixed on the shaft 143 is an upwardly-extending arm 145 connected by a link 146 with the depending link 104, by which the color-signal is controlled and the rocking of the shaft 143, just described, will cause the link 104 to be moved forwardly out of the 65 path of the plunger 108.

When the machine is set for subtraction, it may be reset for addition by means of an addition-key 147 mounted on the forward end of a link 148. Upon depression of the addition-key 147, a pin 149 projecting to the right from the link 148 engages a cam 150 on a lever 151 and rocks the latter about its pivot 152. The pivot 152 projects on opposite sides of an upright post 153, and the lever 151 is connected by a bridge 154 with an arm 155 at the front of the post 153, so that, upon rocking the lever 151, the arm 155 is depressed and a pin 156, projecting through a slot 157 in a vertical key-stem 158, depresses the latter against the resistance of a spring 158^a and acts through a lever 159, attached at its forward end to said key-stem 158 and pivoted at its rear end at 160, to rock the lever 136 and cause the general operator to effect a complete 80 cycle and set the machine for addition. During the forward movement of the general operator the shaft 62 is rocked to cause a cam 161 thereon to engage and lift a bar 162 to cause a pin 163 on the upper end thereof 85 to lift a tail 164 of the lever 151. The bar 162 has a pin-and-slot connection 165 with an arm 166 loosely pivoted on the shaft 62. The addition-key 147 should be held in depressed position until the return movement 90 of the general operator is completed and the lever 151 restored to its normal position. The pin 149 is then to the rear of a shoulder 95 167 at the rear end of the cam 150, and the addition-key is held in depressed position 100 until released by actuation of the general operator. The key-stem 158 is provided at its upper end with a key 168 by which the general operator may be thrown into operation 105 at will.

Adjacent the rear end of the link 148 is a lever 169 pivoted on the ceiling 170 of the computer-casing 71 by means of a shouldered screw 171 and pivoted at its forward end to the link 148 by means of a shouldered screw 172. At its rear end the lever 169 is provided with a cam 173 to control the color-changing mechanism when the link 104 is shifted out of the path of the plunger 108 connected to the subtraction-setting mechanism. At the rear of the shouldered screw 171 the lever 169 is connected with the link 148 by means of a spring 174, which tends to hold the link 148 in its forward position and the cam 173 in ineffective position. The cam 173 is provided with a comparatively shallow end 175, over which the link 104 lies, and is also provided with an incline 176 which, upon depression of the addition-key 147, engages the lower end of the link 104 and lifts the same to shift the color-signal to indicate typing in red.

Provision is also made of a non-compute finger-piece or key 177 at the upper end of 130

a lever 178 mounted on a pivot 179 on the fixed part of the typewriter-frame. At its lower end the lever 178 is operatively connected with a portion of the pin 163, lying 5 to the right of the bar 162, by means of a fork at the lower end of the lever 178 embracing said pin 163 and permitting the pin to be raised and lowered without breaking the operative connection. The pin 163 10 is connected to the forward end of a link 180, which, when urged rearwardly against the action of a spring 181, swings a bell-crank lever 182 about its pivot 183, and, through a rearwardly-extending arm 184 15 thereof in engagement with an arm 185 projecting forwardly from a shaft 186, rocks the shaft and arms 187 thereon against the action of a spring 188 and swings the zone-controller 45 rearwardly out of position 20 to co-operate with the frusto-conical roller 46 on the denomination-selector 43. The link 180 is guided in a slotted member 189, and when moved rearwardly is lifted by a cam 190 on the lower side thereof 25 until a shoulder 191 at the forward end of the cam is carried past the slotted member 189, whereupon the link 180 drops with the shoulder 191 in engagement with the rear face of the slotted member 189, and is held 30 in this position until released by the lifting of the pin 163, as a result of the actuation of the general operator. The link 180 is provided near its rear end with a laterally-projecting pin 192, which, upon rearward 35 movement of the link 180, engages the upper end of a lever 193 and rocks it about a pivot 194 against the action of a spring 195. A latch member 196 is also mounted on the pivot 194 and is connected with the lever 40 193 by means of a pin 197 projecting through a slot 198 in the latch member 196 which is constantly urged in a forward direction by means of a spring 199. When the upper end of the lever 193 is swung rearwardly 45 the latch member 196 will be advanced into a position to overlie a pin 200 on the arm 129 of the lever 133 through which the automatic actuation of the general operator is effected, thus preventing automatic action 50 of the general operator while the non-compute key is in depressed position. It should be understood that, due to the pin-and-slot connection between the latch 196 and lever 193 and the action of the spring 199 on the 55 latch member 196, undue strain is avoided if the pin 200 is in raised position at the front of the latch 196 at the time of actuation of the non-compute key.

The mechanism so far described is in general similar to mechanism disclosed in said patent to Adolph G. Kupetz, No. 1,452,162, dated April 17, 1923.

It is desirable to prevent the depression of more than one numeral-key at a time and 65 in certain cases to lock all of the numeral-

keys. To this end each pendant 57 is provided with a rearwardly-extending arm 201 to which is pivoted the upper end of an intruding member 202, which, upon depression of the corresponding numeral-key, is 70 thrust into the gap between two of a set of crowding dogs or hooks 203 swingable about pivots 204 on a transverse bar 205 and confined between two abutments, not shown, but with sufficient play to permit 75 the admission of one of said intruding members 202. For a fuller disclosure of such key-locking means, reference is made to the patent to Frederick A. Hart, No. 1,339,704, dated May 11, 1920. 80

To lock all of the numeral-keys, provision is made of a finger 206 which, when swung into an opening between a dog 203 at one end of the series and the fixed abutment at that end, crowds the dogs so closely together 85 as to prevent the insertion of one of said intruding members 202, and consequently to prevent depression of any one of the numeral-keys. The finger 206 is mounted 90 on a rock-shaft 207 normally urged by a spring 208 to hold the finger 206 in ineffective position.

When, however, the shaft 207 is rocked against the action of the spring 208, the finger 206 is urged toward its effective position, and in order to prevent breakage in case the dogs are already crowded together, provision is made of a yielding connection between the finger 206 and the shaft 207, 100 comprising a spring 209 attached at one end to the finger 206 and at the other end to a finger 210 projecting upwardly from the shaft. The shaft may be rocked by an arm 211 fixed thereon and pivoted at its upper end to the forward end of a link 212, which, at its rearward end, is pivoted to a lever 213 loosely mounted on the subtraction 105 shaft 76.

In said patent to Hart provision is made of means for locking the numeral-keys when the carriage reaches a subtraction zone. According to the present invention, provision is made of carriage-controlled means for locking the numeral-keys when certain computing zones are reached, the mechanism for producing this result being, however, different from that disclosed by Hart. To effect such locking, certain column-stops 118 are provided with extensions 214 so positioned from front to rear as to pass between the dogs 120 and 139 but to engage a dog 215 mounted on a lever 216 also mounted on pivot 122 to draw upwardly a link 217 and to rock a lever 218 connected at its forward end with the lever 213, so as to rock 110 the latter and effect locking of the numeral-keys. 115

The connection between the link 217 and lever 218 is effected by means of a shouldered screw 219 passing through an L-shaped 120 130

slot 220 in the link 217 and threaded into the lever 218, one branch of the L-shaped slot being horizontal and the other branch projecting downwardly from the forward 5 end of the horizontal branch. Normally the shouldered screw 219 is held at the rear end of the horizontal branch of the slot, and the link 217 is then effective to lift the rear end of the lever 218. When, however, the link 217 is swung rearwardly to bring into alignment the shouldered screw 219 and the vertical branch of the slot 220, lifting of the link 217 will not effect actuation of the lever 218. At its forward end 10 the lever 218 is connected with the lever 213 by a shouldered screw 221 projecting through a slot 222 in the lever 213 and threaded into the forward end of the lever 218, the slot 222 being approximately in 15 the arc of a circle about the axis of the shaft 76, so that the lever 213 may be operated to swing the finger 206 into effective position independently of the lever 218.

In order that the numeral-keys 16 may 20 be unlocked after having been locked by the carriage as it reaches a computing zone, provision is made of means for unlocking the numeral-keys when the subtraction-setting mechanism is operated. To this end provision is made of a link 223 pivoted at 224 on the subtraction-bar 79 and supporting at its other end a pivot 225 of the lever 218, said pivot 225 extending through a slot 226 in a fixed bracket 227. When, therefore, the 25 numeral-keys are locked, as shown in Figure 4, depression of the subtraction-key 72 causes the subtraction-bar 79 to be moved rearwardly by the spring 80 to lift, through the link 223, the forward end of the lever 218 and thereby release the numeral-keys 40 from the locking means.

Provision is also made for releasing the numeral-keys from the locking means by depression of the addition-key 147 or actuation of the non-compute key 177. Such release is effected in both cases by moving the link 217 rearwardly from its normal position to bring the upright branch of the slot 220 in the link 217 below the shouldered 50 screw 219, so as to free the rear end of the lever 218 from control by the link 217. The position of the link 217 is determined by means of a link 228 pivotally connected with the lower end of the link 217 by means of a 55 set-screw 229 and pivoted at its forward end to an upright arm 230 fixed on a shaft 231 journaled at its left-hand end in the fixed bracket 227, and at its right-hand end in a fixed bracket 233, in which the pivot 194 of 60 the lever 193 is supported. As shown in Figure 12, the end of the shaft 231 projects through the bracket 227, and provision is made of a spacer 232^a to cause the lever 218 to clear the end of the shaft 231. The spacer 65 232^a is held in position by the pivot 225,

which may be in the form of a suitable screw. Fixed on the right-hand end of the shaft 231 are two members 234 and 235 secured together by any suitable means, such as rivets 236, the member 234 having its upper end bent to the right, back of the lever 193, and the upper end of the member 235 having connected therewith a spring 237 to urge it forwardly, and, through the various connections, hold the link 217 in its 75 forward position.

As previously described, the upper end of the lever 193 is swung rearwardly when the non-compute key 177 is actuated, and this movement is transmitted through the member 234 and other connecting parts to the link 217 to swing the same rearwardly to ineffective position. To release the numeral-keys by means of the addition-key 147, provision is made of a slide 238 resting on the ceiling 170 of the computer, and having at its forward end a finger 239 embracing a pin 240 by which one end of the spring 174 is attached to the link 148. The slide 238 is guided near its rear end by a shouldered screw 241 projecting through a slot 242 therein, and threaded into the ceiling 170 of the computer-casing, said slide 238 being provided with a shoulder 243 to engage the upper end of the member 235 to rock the shaft 231 and shift the lower end of the link 217 rearwardly to release the locked numeral-keys. To determine the normal position of the lever 218, provision is made of a stop 244 supported on the bracket 227 by means of clamping screws 245 passing through a slot 246 in the stop and threaded into the bracket 227. In order that the lower end of the link 217 may be supported at the proper 100 position, provision is made of an adjustment screw 247 connecting the upper end of the link 217 to the body thereof.

As indicated in Figures 1 and 3, the color-controlling link 104 normally overlies both the plunger 108, controlled by the subtraction-setting mechanism, and the cam 173 controlled by the addition-key 147, the arrangement being the same as in said patent to Kupetz No. 1,452,162. It will be seen that, due to this arrangement, typing may be effected in red outside of the computing zone by merely depressing the addition-key without changing the normal addition setting of the machine. In said Patent No. 1,452,162 the rearward position of the color-controlling link is determined by the rear end of a guide slot, but, according to the present invention, the slot 105, through which the link 104 passes, is extended rearwardly to enable the link to be drawn to the rear of the cam 173 under the urging of the spring 144 which surrounds the shaft 143.

The link 104 is, however, maintained in a proper normal position by means of an arm 248 having a pin 249 thereon engaging

an abutment in the form of a link 250 with an upper forked end embracing the shaft 143 pivoted at its lower end on the shoulered screw 229. The link 250 is, however, 5 provided with a notch or recess 251 immediately beneath the normal point of contact of the pin 249 with the link, so that, when the link 217 is lifted to lock the numeral-keys, the link 250 is lifted sufficiently to 10 bring the notch 251 opposite the pin 249, thereby permitting the arm 248 to be swung downwardly by the spring 144, and the color-changing link 104 swung rearwardly from the path of the cam 173, thus placing 15 the color-changing mechanism entirely under the control of the subtraction-setting mechanism.

As indicated in Figure 3, the machine is set up for three different computing zones. 20 To this end the carriage 22 is provided with three suitably set denomination-selectors 43 and with correspondingly set column-stops 118, of which the one to the left is provided with an extension 138 to cause the color- 25 changing link 104 to be advanced out of the path of the plunger 108 and placed under the exclusive control of the cam 173 actuatable by the addition-key 147, and with a shorter extension 214 to the front of the extension 138 and positioned to actuate the key-locking mechanism through the link 217. The second column-stop 118 is provided only with an extension 214 to effect the locking of the keys, and the third column-stop 118 30 has no extension such as 138 and 214, and therefore has no control of the key-locking mechanism or the color-shifting mechanism but is effective, as in the case of the other column-stops, to automatically throw the 35 general operator into operation as the carriage passes out of the corresponding computing zone.

When the carriage reaches the computing zone corresponding to the left-hand column-stop 118, the extension 138 engages the dog 139 and shifts the color-changing link 104 out of the path of the plunger 108, and when the carriage is advanced further the extension 214 on the left-hand column-stop 50 engages the dog 215 and acts through the link 217 to lock the numeral-keys. The different parts will then be in the position indicated in Figure 4.

If subtraction is to be effected in this 55 column, which is hereinafter referred to as the first column, the subtraction-key 72 is depressed; and, as shown in Figure 5, the state-signal link 116 is lifted to cause the "S" on the state-signal to be shown through the 60 opening 93 in the black color field at the sight-opening 94, and to cause the link 223 to be brought to a substantially vertical position, thereby lifting the forward end of the lever 218 to unlock the numeral-keys. 65 After a number to be computed in the first

column is typed, the general operator is automatically thrown into operation and the parts restored to their normal position, the extensions 138 and 214 of the column-stop having at this time passed beyond the 70 dogs 139 and 215 and released the same.

If it is desired to add in the first column, the addition-key 147 is depressed and the color-signal shifted as shown in Figure 6, 75 to show the "A" of the state-signal through the red field of the color-signal at the sight-opening 94. At the same time the slide 238 is moved rearwardly to rock the lever 193, and through the shaft 231 and link 228 to shift the link 217 rearwardly to the position 80 shown in Figure 6, thereby permitting the shouldered screw 219 to drop in the vertical branch of the slot 220, and permitting the forward end of the lever 218 to be lifted to render the key-lock of the numeral-keys ineffective by withdrawal of the finger 206 from effective position.

After the typing in the first computing column has been completed, the carriage may be tabulated in the usual manner to the second column, extension 214 on the corresponding column-stop acting as in the first column to lock the numeral-keys, and by upward shifting of the link 250 to permit the color-shifting link 104 to be swung 95 rearwardly out of the path of the cam 173, as indicated in Figure 7. If it is desired to effect subtraction in the second column, the subtraction-key is first depressed, as shown in Figure 8, to release the subtraction-bar, thereby effecting, through the link 223, a lifting of the forward end of the lever 218 to release the numeral-key lock and to effect, through the plunger 108, shifting of both the state and color signals. The "S" indication of the state-signal will then be displayed through the red color-field of the color-signal to indicate red subtraction. Upon passage of the carriage out of the second computing zone or column, the parts 100 will be restored automatically to their normal position.

If it is desired to add in the second column, the addition-key 147 is depressed, as indicated in Figure 9, thereby acting through the slide 238, shaft 231 and link 228 to swing the link 217 rearwardly to the position shown in Figure 9, and permitting the shouldered screw 219 to drop in the vertical branch of the slot 220, thereby effecting release of the numeral-key lock. In this column, however, the color-controlling link is positioned to the rear of the cam 173, and consequently depression of the addition-key has no effect on the color-changing mechanism, so that both the state and color signals are in their normal positions, as indicated in Figure 9.

Inasmuch as the column-stop 118 for the 110 third column lacks both projections or ex-

tensions 214 and 148, there is no locking of the numeral-keys for this zone, and no shifting of the color-controlling link from its normal position. If, then, the subtraction-setting key is depressed, the machine is set for subtraction in the usual manner and both signals shifted to indicate red subtraction. If it is desired to effect addition in this zone no actuation of the addition-key is usually necessary, since the machine is normally set for addition. If, however, the machine is set for subtraction at this time, depression of the addition-key acts through lever 151, key-stem 158 and their associated parts to throw the general operator into operation to re-set the machine for addition, and through the cam 173 will effect a setting of the color-controlling link 104 to cause typing in red. By depression of the key 168, however, the carriage is merely set for black addition.

If it is desired to type numbers in the different columns without computing, the machine may be set for this purpose by actuating the non-compute key 177 to shift the zone-controller 145 rearwardly to render the denomination-selecting mechanism ineffective, and, if the machine is in a computing zone for which locking of the keys is effected, the numeral-keys are released, as hereinbefore described, by means of the pin 192 on the non-compute link 180 rocking the lever 193 to effect, through the shaft 231 and other connections, the rearward movement of the link 217 to ineffective position. When the computing mechanism is thus rendered ineffective by means of the non-compute key 177, the color-changing mechanism, for which there is no direct manual control, may be set, as desired, by means of the addition and subtraction keys.

Variations may be resorted to within the scope of the invention, and portions of the improvements may be used without others.

Having thus described my invention, I claim:

1. In a combined typewriting and computing machine, numeral-keys, a carriage, carriage-controlled means for determining computing zones, carriage-controlled means for locking the numeral keys when the carriage reaches a computing zone, an addition-key, and means actuatable by said addition-key for releasing said numeral-keys.

2. In a combined typewriting and computing machine, numeral-keys, a carriage, carriage-controlled means for determining computing zones, carriage-controlled means for locking the numeral keys when the carriage reaches a computing zone, an addition-key, a subtraction-key, and means actuatable by said addition-key or by said subtraction-key for releasing said numeral-keys.

3. In a combined typewriting and computing machine, numeral-keys, a carriage,

carriage-controlled means for determining computing zones, carriage-controlled means for locking the numeral-keys when the carriage reaches a computing zone, an addition-key, a non-compute key, and means actuatable by said addition-key or by said non-compute key for releasing said numeral-keys.

4. In a combined typewriting and computing machine, numeral-keys, a carriage, carriage-controlled means for determining computing zones, carriage-controlled means for locking the numeral-keys when the carriage reaches a computing zone, an addition-key, a subtraction-key, a non-compute key, and means actuatable by said addition-key, said subtraction-key or said non-compute key for releasing said numeral-keys.

5. In a combined typewriting and computing machine, a traveling carriage, an addition-key, a subtraction-key, color-changing mechanism normally shiftable by actuation of either the addition-key or the subtraction-key, and carriage-controlled means for freeing said color-changing mechanism from control by said addition-key.

6. In a combined typewriting and computing machine, a traveling carriage, an addition-key, a subtraction-key, color-changing mechanism normally shiftable by actuation of either the addition-key or the subtraction-key, and carriage-controlled means for freeing said color-changing mechanism from control by said subtraction-key.

7. In a combined typewriting and computing machine, a traveling carriage, an addition-key, a subtraction-key, color-changing mechanism normally shiftable by actuation of either the addition-key or the subtraction-key, and carriage-controlled means for freeing said color-changing mechanism from control by said addition-key or from control by said subtraction-key.

8. In a combined typewriting and computing machine, a traveling carriage, numeral-keys, an addition-key, a subtraction-key, color-changing mechanism shiftable by actuation of either the addition-key or the subtraction-key, carriage-controlled means for locking said numeral-keys, means controlled by said locking means for freeing said color-changing mechanism from control by said addition-key, and means actuatable by said subtraction-key for releasing said numeral-keys from said locking means.

9. In a combined typewriting and computing machine, a traveling carriage, numeral-keys, an addition-key, a subtraction-key, color-changing mechanism shiftable by actuation of either the addition-key or the subtraction-key, carriage-controlled means for locking said numeral-keys, means controlled by said locking means for freeing said color-changing mechanism from control by said addition-key, and means actuatable by said subtraction-key for releasing said numeral-keys from said locking means.

able by said addition-key for releasing said numeral-keys from said locking means.

10. In a combined typewriting and computing machine, a traveling carriage, numeral-keys, an addition-key, a subtraction-key, color-changing mechanism shiftable by actuation of either the addition-key or the subtraction-key, carriage-controlled means for locking said numeral-keys, means controlled by said locking means for freeing said color-changing mechanism from control by said addition-key, and means actuatable by said addition-key or said subtraction-key for releasing said numeral-keys from said locking means.

11. In a combined typewriting and computing machine, a traveling carriage, numeral-keys, an addition-key, a subtraction-key, a non-compute-key, color-changing mechanism shiftable by actuation of either the addition-key or the subtraction-key, carriage-controlled means for locking said numeral-keys, means controlled by said locking means for freeing said color-changing mechanism from control by said addition-key, and means actuatable by said addition-key, subtraction-key or non-compute-key for releasing said numeral-keys from said locking means.

12. In a combined typewriting and computing machine, a carriage, numeral-keys, a subtraction-key, means controlled by the carriage for locking the numeral-keys when the carriage reaches a computing zone, said locking means comprising a longitudinally-shiftable link, and a lever operable by said link and connected therewith by a pin projecting into a right-angle slot in the link and normally in the proper branch of the slot to provide an operative connection, and means to effect relative displacement between the lever and the link to cause the pin to lie in the other branch of the slot, thereby breaking the effective connection.

13. In a combined typewriting and computing machine, a carriage, numeral-keys, a subtraction-key, means controlled by the carriage for locking the numeral-keys when the carriage reaches a computing zone, said locking means comprising a longitudinally-shiftable link, and a lever operable by said link and connected therewith by a pin projecting into a right-angle slot in the link and normally in the proper branch of the slot to provide an operative connection, subtraction-key-actuated means for releasing said numeral-keys from said locking means, and means to effect relative displacement between the lever and the link to cause the pin to lie in the other branch of the slot, thereby breaking the effective connection.

14. In a combined typewriting and computing machine, a carriage, numeral-keys, a subtraction-key, an addition-key means controlled by the carriage for locking the nu-

meral-keys when the carriage reaches a computing zone, said locking means comprising a longitudinally-shiftable link, and a lever operable by said link and connected therewith by a pin projecting into a right-angle slot in the link and normally in the proper branch of the slot to provide an operative connection, and addition-key-actuated means to effect relative displacement between the lever and the link to cause the pin to lie in the other branch of the slot, thereby breaking the effective connection. 75

15. In a combined typewriting and computing machine, a carriage, numeral-keys, a subtraction-key, an addition-key, a non-compute-key, means controlled by the carriage for locking the numeral-keys when the carriage reaches a computing zone, said locking means comprising a longitudinally-shiftable link, and a lever operable by said link and connected therewith by a pin projecting into a right-angle slot in the link and normally in the proper branch of the slot to provide an operative connection, and means actuatable by said addition-key or said non-compute-key to effect relative displacement between the lever and the link to cause the pin to lie in the other branch of the slot, thereby breaking the effective connection. 80 85

16. In a combined typewriting and computing machine, a carriage, numeral-keys, a subtraction-key, a non-compute-key, means controlled by the carriage for locking the numeral-keys when the carriage reaches a computing zone, said locking means comprising a longitudinally-shiftable link, and a lever operable by said link and connected therewith by a pin projecting into a right-angle slot in the link and normally in the proper branch of the slot to provide an operative connection, and non-compute-key actuated means to effect relative displacement between the lever and the link to cause the pin to lie in the other branch of the slot, thereby breaking the effective connection. 90 95 100

17. In a combined typewriting and computing machine, a carriage, addition-setting mechanism, subtraction-setting mechanism, color-changing mechanism normally under the control of said addition-setting mechanism and said subtraction-setting mechanism, and carriage-controlled means for freeing said color-changing mechanism from control of either said addition-setting mechanism or said subtraction-setting mechanism and placing it under the exclusive control of the other of said mechanisms. 115 120

18. In a combined typewriting and computing machine, a carriage, numeral-keys, addition-setting mechanism, subtraction-setting mechanism, color-changing mechanism normally under the control of said addition-setting mechanism and said subtraction-setting mechanism, carriage-controlled means 125 130

- for freeing said color-changing mechanism from control of either said addition-setting mechanism or said subtraction-setting mechanism and placing it under the exclusive 5 control of the other of said mechanisms, and numeral-key-locking means settable by said carriage upon reaching a computing zone, and releasable by actuation of either said addition-setting mechanism or said subtraction-setting mechanism.
19. In a combined typewriting and computing machine, numeral-keys, a carriage, carriage-controlled means for determining computing zones, carriage-controlled means, 15 including a train of connections, for locking the numeral-keys when the carriage reaches a computing zone, an addition-key, a subtraction-key, addition-key-actuated means for rendering said train of connections ineffective at one point, and subtraction-key-actuated means for rendering said train of connections ineffective at another point.
20. In a combined typewriting and computing machine, numeral-keys, a carriage, carriage-controlled means for determining computing zones, carriage-controlled means, including a train of connections, for locking the numeral-keys when the carriage reaches 30 a computing zone, an addition-key, a subtraction-key, a non-compute-key, subtraction-key-actuated means for rendering said train of connections ineffective at one point, and means actuatable either by said addition-key or by said non-compute-key for rendering said train of connections ineffective at another point.
21. In a combined typewriting and computing machine, numeral-keys, a carriage, 40 carriage-controlled means for determining computing zones, carriage-controlled means, including a train of connections, for locking the numeral-keys when the carriage reaches a computing zone, a subtraction-key, a non-compute-key, subtraction-key-actuated means for rendering said train of connections ineffective at one point, and subtraction-key-actuated means for rendering said train of connections ineffective at another point.
22. In a combined typewriting and computing machine, a traveling carriage, color-changing mechanism normally set for one color, means including a reciprocable member for shifting said color-changing mechanism, subtraction-setting mechanism including an actuating member for said reciprocable member, addition-setting mechanism including a second actuating member 55 for said reciprocable member, means normally urging the end of the reciprocable member adjacent said actuating members to one side, means including a shiftable abutment for normally holding such end of said reciprocable member in position to be engaged by said actuating members, carriage-controlled means for shifting said reciprocable member against said urging means out of the path of one of said actuating members, and carriage-controlled means for shifting said abutment to effective position to permit said reciprocable member to be drawn by said urging means out of the path of the other actuating member.
23. In a combined typewriting and computing machine, a carriage for determining computing zones, color-changing mechanism including a pendent link, addition-setting mechanism including a lifter under said link, subtraction-setting mechanism including a second lifter under said link, means including a swingable arm connected to said link and a spring, to urge said link out of the path of the first lifter, a shiftable abutment to obstruct said arm and hold said link against the action of said urging means, and carriage-actuated means to shift said abutment to release said arm and permit movement of the link out of the path of the first lifter.
24. In a combined typewriting and computing machine, a carriage for determining computing zones, color-changing mechanism including a pendent link, addition-setting mechanism including a lifter under said link, subtraction-setting mechanism including a second lifter under said link, means for urging said link out of the path of the addition-setting lifter, including a rock-shaft and a spring to rock said shaft, means to restrain said shaft comprising an arm fixed thereon, a pin projecting laterally from said arm, and a slid able abutment normally engaging said pin and having a notch to permit release of the shaft when the notch is brought opposite said pin, and carriage-actuated means for shifting said abutment to release said shaft to the action of said spring.
25. In a combined typewriting and computing machine, a carriage, numeral-keys, addition-setting mechanism, subtraction-setting mechanism, color-changing mechanism normally under control of both said addition-setting and said subtraction-setting mechanisms, means including a spring for destroying such control by one of said setting mechanisms, means normally restraining said control-destroying means, numeral-key-locking means, carriage-controlled means effective upon reaching a computing zone for rendering said locking means effective and concomitantly rendering said restraining means ineffective, and means actuatable either by said addition-setting mechanism or by said subtraction-setting mechanism to release said numeral-key-locking means without changing the control of said color-changing mechanism.
26. In a combined typewriting and computing machine, a carriage for determining computing zones, color-changing mechanism including a pendent link, addition-setting mechanism including a lifter under said link, subtraction-setting mechanism including a second lifter under said link, means including a shiftable abutment to obstruct said arm and hold said link against the action of said urging means, and carriage-actuated means to shift said abutment to release said arm and permit movement of the link out of the path of the first lifter.

- puting machine, a carriage, numeral-keys, addition-setting mechanism, subtraction-setting mechanism, color-changing mechanism normally under control of both said addition-setting and said subtraction-setting mechanisms, means including a spring for destroying such control by one of said setting mechanisms, means normally restraining said control-destroying means, numeral-key-locking means, carriage-controlled means effective upon reaching a computing zone for rendering said locking means effective and concomitantly rendering said restraining means ineffective, carriage-controlled means effective upon reaching another computing zone for rendering said locking means effective and overcoming such spring to destroy the control of the setting mechanism which the spring tends to establish, and means actuatable either by said addition-setting mechanism or by said subtraction-setting mechanism to release said key-locking means for each of said zones.
27. In a combined typewriting and computing machine, a carriage, numeral-keys, numeral-key-locking means, and carriage-actuated means for rendering said locking means effective, comprising a longitudinally-shiftable link having an L-shaped slot, and a member having a pin projecting into said slot to effect an operative connection when the pin is in one branch of the slot and to render the connection ineffective when in the other branch of the slot.
28. In a combined typewriting and computing machine, a carriage, numeral-keys, numeral-key-locking means, an addition-key, a subtraction-key, bichrome mechanism controllable by said addition-key or said subtraction-key, and a link shiftable upwardly by the carriage to change the control of the bichrome mechanism and to render the locking means operative, and shiftable in another direction to release said key-locking means without changing the control of said bichrome mechanism.
29. In a combined typewriting and computing machine, a carriage, numeral-keys, means for locking said numeral-keys, and means actuatable by said carriage to render said locking means effective and comprising a link adjustable as to length.
30. In a combined typewriting and computing machine, a carriage, numeral-keys, numeral-key-locking means, means including a link liftable by the carriage for rendering said locking means effective, bichrome mechanism, a link for controlling said bichrome mechanism, two actuators for said controlling link, means to place the controlling link under the control of one or the other of said actuators and including a shaft, a spring tending to shift in one direction an arm fixed on the shaft and having a pin projecting laterally therefrom, and a link slotted to embrace said shaft and connected at its lower end to the key-locking link to be lifted and lowered therewith and having a suitably positioned notch, so that when the key-locking link is in its lower position the pin will rest against the slotted link and will be held against actuation by the spring, and when the key-locking link is in raised or effective position the notch in the slotted link will be opposite said pin and the shaft will be released.
31. In a combined typewriting and computing machine, a carriage, numeral-keys, an addition-key, a subtraction-key, bichrome mechanism controlled by said addition-key and said subtraction-key, numeral-key-locking means, and carriage-actuated means including a link for rendering the locking means effective, and changing the control of said bichrome mechanism, and a second link for changing the control of said bichrome mechanism independently of said locking means.
32. In a combined typewriting and computing machine, a carriage, numeral-keys, a numeral-key-lock, an addition-key, a subtraction-key, bichrome mechanism controllable by said addition and said subtraction-keys, and carriage-controlled means effective in one zone for rendering said lock effective and placing the bichrome mechanism under the control of the addition-key and in another zone for rendering the lock effective and placing the bichrome mechanism under the control of the subtraction-key.
33. In a combined typewriting and computing machine, a carriage, a rock-shaft urged in one direction by a spring, an arm on said shaft and having a laterally-projecting pin, and a member slotted to embrace said shaft and serving as an abutment to be engaged by said pin in restraining the movement of the shaft and being provided with a notch to release said pin when brought opposite the same by shifting the slotted member.
